UNITED STATES PATENT OFFICE.

JULIUS B. GROND, OF NEW YORK, N. Y.

COOLING AND REFRIGERATING SYSTEM.

Application filed January 9, 1925. Serial No. 1,417.

This invention relates to improvements in a cooling and refrigerator system, and has for its object to provide a system not requiring the use of ice.

5 Another object of this invention is to provide in a cooling and refrigerating system, a suitable compartment, and means for creating a rapid evaporation of water.

A still further object of this invention is 10 to provide in a cooling and refrigerating system, a series of curtains and means whereby the curtains may be kept moist through their entire surfaces.

A further object of this invention is to 15 provide in a cooling and refrigerating system, curtains and means for keeping said curtains thoroughly wet, and means for continuously forcing air currents substantially over the entire surfaces of said curtains.

20 A still further object of this invention is to provide in a cooling and refrigerating system requiring compressed air for causing rapid evaporation of moisture, a means for cooling said air.

25 With the foregoing and other objects in view, I have invented the system illustrated in the accompanying drawings, in which:

Figure 1 is a vertical sectional view of a refrigerating room embracing my invention.

30 Figure 2 is a section at line 2—2 thereof; Figure 3 is a detail longitudinal sectional view of a water supply tank;

Figure 4 is a section on line 4—4 thereof;

Figure 5 is a detail of a side elevational 35 view of a valve member; and

Figure 6 is an enlarged detail section of a gutter.

Like reference characters indicate like parts throughout the several views of the 40 drawings and in the specification, in which 1 indicates a refrigerating room having a gutter 2, extending entirely therearound. From this gutter is suspended a series of curtains 3, 4 and 5, by means of hooks 6 and 6' attached thereto, at suitable intervals adjacent but spaced apart from the upper edge 45 thereof. These hooks 6 and 6' are adapted to engage over the edges 7 on the roll of the edge 8 of the gutters 2 and on the edge 7' of gutter 15. The portion 9 of the said curtains, above the hooks 6, are adapted to lie loosely over said roll 8 and into the bottom 50 of the gutter 2. It is to be noted at this point that the curtains are not stretched in any direction over the roll 8, but by means

of their suspension through the said hooks, which are slidable and movable over the edge 7, remain loose at all times. This is in order that the weight of the water when the curtains become saturated, will not draw 60 the curtains taut over the roll 8 of the gutter 2, thus permitting the curtains to readily absorb the water and siphon it from the gutter, to a sufficient extent to keep the entire curtains saturated at all times. Mounted 65 behind the curtains 3, 4 and 5, and substantially there-against, are a series of horizontally disposed back pipes 10, each having a series of suitably spaced apart nozzles 11, projecting toward the curtains. These pipes 70 10 are connected to an air supply pipe line 12, through valves 13, in order to control the supply of air to each of the horizontal pipes. The lower edges 14 of the curtains depend into a gutter 15, which inclines toward a 75 water inlet pipe 16 of the water supply tank 17, so that any water draining upon the curtains will return to the tank 17 from which it is originally supplied to the gutter 2, in the manner presently to be explained. 80

The principal purpose of the gutter 15, in conjunction with the gutter 2, is that both the upper and lower edges of the curtains 3, 4 and 5 are immersed in water in said gutters to a sufficient extent in order to insure 85 complete saturation of the curtains at all times whereby an air seal is provided which will prevent air from the pipes from escaping over or around the edges of the curtain into the refrigerating or cooling room, thus 90 necessitating all air from the air pipes passing directly through the interstices of the saturated curtain in order to provide rapid evaporation of the moisture in the curtain.

A further water supply to the gutter 15 95 may be provided through a faucet 18. A series of spaced apart uprights 19, terminating in curved upper edges 20, form supports for the screen sections 21, which enclose the curtains and air pipes above described. Mounted outwardly of these screens are a series of batten frames 22, for protecting 100 said screens from the contents of the refrigerating room.

17 is an airtight tank for containing water under air pressure, whereby the same may be supplied to the gutter 2, by automatic means now to be explained. Mounted within the tank 17, is an upright rod 23 over which is movably mounted a tube 24, hav- 110

ing a fixed collar 25 adjacent its lower end, and a head 26 on its upper end. Loosely mounted over the tube 24 is a float 27, which, when the tank is full, will bear against the head 26 and raise the tube 24, operating toggles 28 and 29, on the lower end of tube 24 which are pivoted to the inner ends of levers 30 and 31, both of which are pivoted upon fulcrums 32 and 33 respectively. 5
10 Mounted upon the outer end of the lever 30 is a closure valve 34 for the inlet 35 of the water supply pipe 16 in the gutter 15. Pivoted to the toggle 28 is the inner end of the lever 30. The inner end of lever 31 is pivoted to toggle 29 as at 36. The outer end of lever 31^b is pivoted at 37 to link 38, the upper end of which is pivoted to the arm 39 on the valve plate 40, which plate is provided in its inner surface with an elongated 15 groove 41. The groove 41 in the position as shown in the drawing is adapted to connect the ports 42, 46 and 47, in disc 44. The ports 42 and 46 are supplied by a pipe line 48 with air from an air compressor (not 20 shown), while the port 47 is connected with the supply pipe 12 for the blow pipes 10. In another position the valve plate 40, which is pivotally mounted at 45, is adapted to connect the opening 43, in plate 40, with the 25 port 42 in the disc 44. It is to be noted at this point that the air will steadily pass from port 46, all along the elongated groove 41 to the outlet port 47 and supply pipes 12 and 10. When the water in the tank 17 has risen 30 to its predetermined capacity, the float 27 bearing against the head 26 raises the tube 24 where the toggles 28 and 29 are pivoted, the toggle 28 to inner end of lever 30, causing the valve 34, mounted on the outer end of the 35 lever to close port 35, to prevent outflow of water from said port. At the same time the toggle 29 lifts the inner end of lever 31, forcing outer end 31^b down, causing the link 38 to draw down the arm 39 to connect the 40 ports 42 and 43, to admit compressed air into the upper part 49 of the tank, by means of which the water therein will be forced out through the port 50 into a pipe 51 which supplies the gutter 2. As soon as the water 45 in the tank falls to a level to permit the float 27 (shown dotted in its lower position) to seat upon the collar 25, forcing the tube 24 to its lowermost position which operates the toggles 28 and 29, the operation of the 50 levers 30 and 31 are reversed closing the compressed air inlet port 43, and opening the water inlet port 35, in order to permit the tank to refill as shown by the drawing. Thus, it will be seen that the supply of water 55 to the gutter 2 is automatic. Fixed to the arm 39^b is a rod 52, carrying a closure valve 53 which, when lowered, opens the port 54 to permit the escape of air from the tank 17,

when filling. When the arm 39 is drawn down by the link 38, the valve is caused to close the inlet 54. 65

The automatic means for supplying water for the curtains is the tank 17 above described, and is for use in refrigerating and cooling plants where no normal water pressure supply is available. Where there is a water pressure supply available, such as city water systems the automatic tank will be omitted and I use a supply tank 55, for supplying the water to the upper gutter 2, the supply being controlled for the tank by a valve 56, in the supply pipe 57, said valve 56 being regulated to permit the desired amount of water to keep curtains saturated, to continually flow therethrough, and down the curtains to gutter 15, from where the surface water is drawn by pipe 16. 70

60 is a compressed air cooler, through which compressed air is run from an air compressor (not shown), in order that the heated compressed air may be cooled before being allowed to enter the tank 17. If tank 17 is omitted, the air will pass directly from pipe 58 to pipe 12. 85

Having described my invention that which I claim to be new and desire to procure by Letters Patent is:

1. In a refrigerating system, a gutter, curtains suspended from said gutter, means for preventing the curtains from becoming taut, and means for directing an air current continually against said curtains, substantially throughout its entire surface, said last means consisting of a series of spaced apart air pipes each having a series of nozzles directed toward said curtain. 90

2. In a refrigerating system, a gutter, curtains suspended from said gutter, means for preventing the curtains from becoming taut, and means for directing an air current continually against said curtains substantially throughout its entire surface, said last means consisting of a series of spaced apart air pipes each having a series of nozzles directed toward said curtain, and means for forcing air under pressure through said pipes. 105

3. In a refrigerating system, a gutter, curtains suspended from said gutter, means for preventing the curtains from becoming taut, and means for directing an air current continually against said curtains substantially throughout its entire surface, said last means consisting of a series of spaced apart air pipes each having a series of nozzles directed toward said curtain, and means for forcing air under pressure through said pipes, and means for cooling said air prior to its passage through said pipes. 115

In testimony whereof I affix my signature. 120
JULIUS B. GROND. 125
